UNITED STATES PATENT OFFICE.

ADONIRAM J. KINNAIRD, OF STANDISH, MISSOURI.

GATE.

SPECIFICATION forming part of Letters Patent No. 578,245, dated March 2, 1897.

Application filed September 12, 1896. Serial No. 605,633. (No model.)

To all whom it may concern:

Be it known that I, ADONIRAM J. KINNAIRD, of Standish, Carroll county, Missouri, have invented certain new and useful Improvements in Gates, of which the following is a full, clear, and exact description, reference being had to the accompanying drawings, forming a part thereof.

My invention relates to gates, and more particularly to that class which may be both opened and closed by a person upon a vehicle.

The object of my invention is to produce a gate of this character which is positive and reliable, easy of operation, and simple, strong, durable, and inexpensive of construction.

With this object in view the invention consists in certain novel and peculiar features of construction and combinations of parts, as will be hereinafter described and claimed.

In order that the invention may be fully understood, I will proceed to describe it with reference to the said accompanying drawings, in which—

25 Figure 1 represents a plan view of a gate embodying my invention. Fig. 2 represents, on an enlarged scale, a section taken on the line II II of Fig. 1. Fig. 3 represents a longitudinal section of a bar which carries the 30 gate-operating mechanism. Fig. 4 represents a perspective view of a gate provided with a slightly-modified form of operating mechanism. Fig. 5 is a top plan view of the same.

Similar reference-numerals designate corresponding parts in all of the figures.

1 designates the hinge-post of a gate 2, and 3 the latch-post, provided with the customary hook-catch 4.

The latch is a compound latch, comprising 40 a front piece 5, pivotally mounted to operate in a vertical plane, as at 6, upon the gate and adapted to engage the hook 4 at its front end, and a piece 7, which is pivotally mounted, as at 8, upon the gate and is stepped upon or 45 into the rear end of the piece 5, so that when the front end of said piece 7 is depressed it pivotally operates the piece 5 and disengages it from the hook 4.

10 designates a diagonal brace which is 50 secured to the longitudinal rails 8 and bears at its lower end against the front bar thereof and at its rear end is bolted, as at 11, to the

upwardly-extending end of the rear bar of the gate. This diagonal brace obviously prevents any possible sagging of the gate at its 55 front end while in operation or when standing open or closed. Secured rigidly in the plane of and to the top rail of the gate and said diagonal brace is the supporting-bracket 12 for the lever-supporting bar 13, which projects rearwardly from the gate and at an angle of about forty-five degrees from the longitudinal plane of the same, as shown most clearly in Fig. 1. Adjacent to the hinge of the gate 60 said bar 13 is recessed and carries the oblong bracket 14, extending transversely of said bar, and journaled in the bracket edge to edge are a pair of antifriction-rollers 15, below and between which the bar 13 is provided with a vertical opening 16.

17 designates a rocking lever which is mounted to operate in a horizontal plane upon the bar 13 and at its front end normally overhangs the space between the antifriction-rollers 15, and attached permanently 75 to said end, as shown at 18, is the cord or chain 19, extending vertically downward through the opening 16 and attached at its lower end to the loop or eyebolt 20, secured to the rear end of the compound latch. The 80 movement of said lever is limited by means of the U-shaped bracket 21, secured to the rear end of the bar 13, for a purpose which will hereinafter appear, and the rear end of said lever 17 is connected, as at 22, to the opposite ends of an operating-cable 23, which cable connects and is coiled once or more around a pair of drums 24 and 25, provided with crank-handles 26, by which they are operated. The brackets in which said drums 85 are journaled are mounted upon the horizontal bar or bars 27, which extends or extends at right angles to the gate just back of the hinge-post and preferably vertically below the pivotal point of said lever. Said bar or bars 27 are supported by the hinge-post and one or more posts 28, and the post 28, at the side toward which the gate opens, is arranged the same distance from the hinge-post as the post 3, and is also provided with a hook-catch 90 95 100 105 110 115 120 125 130 135 140 145 150 155 160 165 170 175 180 185 190 195 198 200 205 210 215 220 225 230 235 240 245 250 255 260 265 270 275 280 285 cable 23 extend divergently forward to said drums, in order that a purchase or leverage may be had at the initial or opening movement of the gate. In practice when the gate 5 is in such position a person may drive up straight or from either side, as the bar 27 is sufficiently high to permit the front wheel of the vehicle to pass beneath it, which obviously permits the driver to get very close 10 to the crank-handles of the drums. He then starts to rotate said drum, and this movement obviously first swings the lever in the direction indicated by the arrow, Fig. 1, until it strikes one end of the U-shaped bracket 15 and simultaneously operates and disengages the compound latch from the hook 4. The continued rotatable movement of the drum then causes, by reason of the engagement of the lever 17 with said bracket 21, the gate to 20 swing open, and it will be apparent that by reason of arranging the bar 13 at the angle shown with relation to the gate the leverage upon the gate, through the medium of the lever 17, is continued until the gate assumes its 25 open position at right angles to the position shown in full lines, and the bar 13 extends also at right angles to its normal position.

With the majority of gates of this class when the gate is about half-open and when 30 the leverage is needed most it diminishes, as a rule, but with my construction it will be apparent that when the gate is half-open the leverage is greater than at the beginning of such movement and that it increases as the 35 gate is opened, as will be apparent from the new position (shown in dotted lines) of said lever 17 in Fig. 1. After passing through the gate the operator grasps the other crank-handle 26 and rotates its drum in the proper 40 direction. This of course first swings the lever to the position shown in dotted lines, Fig. 1, and raises the latch from engagement with the hook 29, and the rotatable movement of the drum continuing the gate is 45 swung back to its closed position, the latch, of course, automatically engaging the hook 14 in the customary manner.

The arrangement thus far described is applied approximately in the plane of a gate of 50 ordinary height.

I will now proceed to describe the slightly-modified form. In this form the substitute for the bar 13 is double the length of said bar, and duplicate levers and operating cords 55 or cables are employed, and because of the increased length of said substitute bar it must be arranged at a greater height than any vehicle which may pass through the gate, for a purpose which will be hereinafter 60 made apparent. Referring now to said modified construction, as illustrated in Figs. 4 and 5, it will be noticed, in the first instance, that the hinge-post must also be of increased length, and that to give perfect rigidity to 65 the gate one of its end bars is extended vertically beyond the upper end of said hinge-post, or such a bar may be secured to said end

bar, and the diagonal brace of the gate, also of greater length, is bolted to the upper end of said extended bar. The horizontal bar 13^a 7c is secured rigidly to said extended bar above the top of the hinge-post and extends at the same angle, preferably, as the bar 13, but in this case it projects forwardly beyond the hinge-post and consequently overhangs the 75 roadway, and for this reason must be above the top of any vehicle which may pass through the gate. Said bar to the rear of said hinge-post carries the lever 17, which operates in connection with antifriction-rollers 15, journaled in the bracket 14, and said lever is connected, as before, to the rear end of the latch. At the opposite side of the latch a similar lever 17^a is mounted, and said lever operates in conjunction with a cord 19^a and 80 a pair of similar antifriction-rollers 15^a, journaled in a bracket 14^a, like the bracket 14. The lateral movement of the lever 17 is limited by the bracket 21, and the lateral movement of the bracket 17^a is limited by the 85 bracket 21^a. At the outer ends of the bars 27, as shown in Fig. 4, are mounted brackets which carry the pulleys 30, which preferably 90 are of the double-grooved type, but this is not important, and extending over said pulleys are the operating cords or cables 31 and 32. The inner ends of said cords are attached, as at 22, to the rear end of the lever 17 and carry at their opposite ends the depending handles 33 and 34, respectively. Extending also over said pulleys are a pair of operating-cords 35 and 36, and these are attached at their inner ends, as at 22^a, to the lever 17^a and carry pendently at their opposite ends the operating-handles 37 and 38, respectively. 100

In practice the gate is opened by pulling down upon the handle 34 or 37. In either case the lever 17 or 17^a is operated as before described and causes first the disengagement 110 of the latch from the hook through the medium of the cord 19 or 19^a and next swings the gate to its open position. This of course, by changing the position of the bar 13^a, lifts the handles 33 and 38; and by pulling downward upon either of them the reverse operation 115 takes place and the gate closes.

It will be apparent, by reason of the edge-to-edge position of the antifriction-rollers employed, that the latch-lifting cords 19 19^a 120 always engage one or the other, and consequently friction and wear are reduced to the minimum.

Thus it will be seen that I have produced a gate which embodies all the features enumerated in the statement of invention as desirable, and it will be apparent that various changes may be embodied in the construction of gate which do not involve a departure from the spirit and scope of the invention. 125

Having thus described the invention, what I claim as new, and desire to secure by Letters Patent, is—

1. The combination with a swinging gate,

5 a hook-carrying post, and a latch carried by said gate, for engagement with said hook, and consisting of two sections pivoted to said gate with the rear section overlapping the front section, of a bar carried by and extending at an angle to the gate, and provided with an opening, antifriction-rollers arranged edge to edge above and at opposite sides of said opening, a lever pivoted upon said bar, a cord connecting said lever and the rear end of the rear section of the latch, and extending through the opening of said bar and between said rollers, a bracket to limit the lateral independent movement of said lever, and means 10 to operate said lever, substantially as described.

15 2. The combination with a post, a gate hinged thereto, and provided with a latch, and a hook-carrying post for engagement with

said latch, of a bar carried by and extending 20 at an angle to the gate, and provided with a pair of perforations, and with a pair of anti-friction-rollers over each perforation, a pair of levers mounted upon said bar and having their inner ends overhanging said rollers, 25 flexible connections between said levers and said latch, whereby the lateral movement of the former will disengage the latter from said hook-carrying post, means to operate said levers, and brackets to limit the lateral movement of said levers, independent of the gate movement, substantially as described.

20 In testimony whereof I affix my signature in presence of two witnesses.

ADONIRAM J. KINNAIRD.
